Fig. 1

FIG. 1 is a front elevational view of a combined sign and fountain showing my new design, the rear being a mirror image of the front shown;

FIG. 2 is a top plan view thereof;

FIG. 3 is a modified form of the combined sign and fountain as shown in FIGS. 1 and 2, wherein the modification resides in the shape of the pool;

FIG. 4 is a second modified form of the combined sign and fountain as shown in FIGS. 1 and 2, wherein the modification resides in the shape of the pool; and

FIG. 5 is a third modified form of the combined sign and fountain as shown in FIGS. 1 and 2, wherein the modification resides in the number of sign-fountain units.

I claim:

The ornamental design for a combined sign and fountain, substantially as shown and described.
